FLUORESCENT WHITENING AGENTS

Herbert August Lubs, Westmoreland, and Mario Francesco Sartori, Monroe Park, Del., assignors to E. I. du Pont de Nemours & Company, Wilmington, Del., a corporation of Delaware

No Drawing. Application July 16, 1953,
Serial No. 368,522

8 Claims. (Cl. 260—305)

This invention relates to the production of novel organic compounds which are useful as whitening agents for fibrous material, such as cellulosic fibers or nylon. It is an object of this invention to produce compounds of the above general nature, but which are characterized further by bleach fastness and by correct shade of fluorescence. Additional objects and achievements of this invention will appear as the description proceeds.

The art of whitening or brightening textile fiber and paper is of relatively recent development. It has been found that fibrous materials which normally have a dull, yellowish cast when in the white, unbleached state, become whiter and brighter if treated with agents which fluoresce under ultraviolet light. Presumably the action of the ultraviolet rays present in ordinary daylight is sufficient to excite these agents upon the fiber to emit fluorescence which overcomes the undesirable tinge of color in the unbleached fiber. Best results are obtained when the shade of fluorescence is complementary to that of the unbleached fiber, so that the colors will cancel out each other. Since the most common off-white shade of unbleached cellulosic and nylon fibers is yellowish, the most desirable shade in a fluorescent is blue.

Another very important demand developed by the trade is bleach fastness. Inasmuch as the aforementioned fluorescent agents are generally incorporated into soap and synthetic detergents, which are packaged and marketed for household use, and inasmuch as in household practice laundered articles are often subjected to bleaching with various agents, for instance hypochlorites, it is essential that the fluorescent transferred from the detergent to the fiber shall not be removed or destroyed by the action of bleach. Unfortunately, most of the fluorescent agents now on the market, and having the desirable blue shade, are weak in respect to this qualification of bleach resistance.

In addition to the above two primary qualifications, an agent for the purposes of this invention should be capable of being synthesized economically from readily available materials, and should have sufficient fluorescent power (often referred to as "tinctorial strength") to give the desired effect at a minimum cost. It should also have affinity for cellulose or nylon fiber and should be capable of being dissolved or readily dispersed in water in the concentrations that would normally be used in the treatment of the respective fibers.

Now according to our invention new chemical compounds are synthesized which satisfy to an excellent degree all the foregoing qualifications. The novel compounds of this invention are aromatic triazoles which are obtained by oxidizing ortho amino azo dyes obtained by coupling 2-diazobenzothiazoles to naphthylamines which are free to couple in position ortho to the amino group. They may be defined generally by the formula

wherein R is the 2-C radical of a benzothiazole selected

2

from the group consisting of benzothiazole, its 6-methyl, 6-ethyl, 6-methoxy, and 6-ethoxy derivatives, and the monosulfo and sulfamyl derivatives of any of these. Q is a 1,2-naphthalene radical of the group consisting of naphthalene, and its monosulfo, disulfo, monocarboxy, dicarboxy, and sulfamyl derivatives. The term "sulfamyl" is used here in a generic sense, to include primary sulfamyl (SO_2NH_2), lower monoalkyl sulfamyl, and lower dialkyl sulfamyl; by lower alkyl radicals, we mean radicals having not over 4 C-atoms each. Where the triazole compound has sulfo or carboxy groups, these may be in the form of free acids, or in the form of common salts thereof, preferably water-soluble salts, such as the alkali-metal or ammonium salts.

As typical of the nomenclature of our novel series of compounds, may be named that subgroup which has no stabilizing substituents at all. It may be expressed by the general formula

wherein X designates hydrogen, methyl, methoxy, ethyl or ethoxy, and which may be named 2-(6-X-2-benzothiazolyl)-2 H-naphtho-(1,2)-triazoles.

The compounds having sulfo and carboxy groups are generally water-soluble, and may be applied to textile fiber or paper from an aqueous bath. Those having only sulfamyl substituents or no substituents at all, are of interest as fluorescents for nylon fiber, and may be applied thereto from aqueous dispersions of the finely divided product or from dispersions made by pouring into water a solution of the fluorescent in an organic solvent such as the Cellosolves (lower monoalkyl ethers of diethylene glycol).

Our novel compounds may be synthesized by diazotizing a 6-X-2-amino-benzothiazole (wherein X has the meaning above indicated), or a monosulfo or monosulfamyl derivative thereof, and coupling the diazo compound in acid medium to an amino naphthalene which may have carboxy, sulfo or sulfamyl radicals in the nucleus, but which is adapted for coupling in position ortho to the amino group. The last condition implies that the amino group is located in position 2 while the 1-position is free; or that a 1-naphthylamine is employed which will couple in the 2-position by virtue of having the 4-position blocked due to the presence of a water-solubilizing group in position 4 or 5. Where the amino-benzothiazole selected is free from sulfo groups, two sulfo or two carboxy groups may be present in the naphthylamine component.

The resulting ortho-amino azo compound is then converted into a triazole by oxidation in known manner, for instance by heating in an aqueous solution of cupric ammonium sulfate or in an aqueous alkaline solution of sodium hypochlorite until the color of the intermediate azo dye has essentially disappeared, and then recovering the product in a desired physical or chemical form, for instance in the form of an alkali-metal or ammonium salt.

In the case of the water-soluble compounds of this invention, if it is found that the reaction product after filtering contains residual color, the latter may be destroyed by treating the filtrate with dilute hypochlorite solution or with reducing agents. The solution may also be clarified with charcoal prior to recovery of the dissolved fluorescent agent. The water insoluble fluorescent

agents of this invention may be purified by crystallization from organic solvents or by hypochlorite treatment of an aqueous slurry of the product.

As suitable 2-amino-benzothiazoles for the foregoing purpose may be mentioned 2-amino-benzothiazole, its 6-methyl, 6-ethyl, 6-methoxy and 6-ethoxy derivatives; the monosulfo derivatives of any of these, obtained for instance by sulfonation of same with 20% oleum at room temperature; the alkali-metal or ammonium salts of such sulfo derivatives; and the corresponding sulfamyl derivatives.

As coupling components for the intermediate amino azo dyestuffs prepared above may be used 2-naphthylamine; 1-naphthylamine-4-sulfonic acid, 2-naphthylamine-6-sulfonic acid, and the various isomers of these; the various primary sulfamyl, monoalkyl sulfamyl and dialkyl sulfamyl derivatives of 1- or 2-naphthylamine; 2-amino-naphthalene-3-carboxylic acid; 1-amino- and 2-amino-naphthalene-4,5-dicarboxylic acid; the various 1-amino- and 2-amino-naphthalene-disulfonic acids; and the alkali-metal or ammonium salts of any of the foregoing.

The requisite sulfamyl derivatives of 1- or 2-naphthylamine may be prepared by first acetylating the corresponding naphthylamine with acetic anhydride, to block the amino group; then sulfonating the compound with chlorosulfonic acid to convert it into a sulfonyl chloride. The latter is then treated with the appropriate amine (ammonia, methylamine, ethylamine, dimethylamine, etc.) to obtain the sulfonamide. Finally, hydrolysis with hot hydrochloric acid regenerates the amino group and gives the desired sulfonamide compound.

The requisite Bz-sulfamyl derivatives of 2-amino-benzothiazole may be obtained by reacting an amino-benzene sulfonamide and sodium thiocyanate in the presence of bromine and acetic acid, according to the procedure described by H. P. Kaufmann et al. in Arch. Pharm. 279, 195, 202-3 (1941).

Without limiting this invention, the following examples are given to illustrate our preferred mode of operation. Parts mentioned are by weight.

Example 1

15.0 parts (0.1 mol) of 2-aminobenzothiazole were dissolved in 20 parts of concentrated sulfuric acid and diazotized at 0° to 5° C., with a solution of sodium nitrite in concentrated sulfuric acid. The obtained diazo solution was added to a solution of 27 parts (0.11 mol) of Broenner's acid (2-amino-naphthalene-6-sulfonic acid) sodium salt in 400 parts of water, while keeping the temperature at 0° to 5° C. The acidity was then reduced by the aid of sodium acetate to a weakly acid test on Congo red paper and the mixture was allowed slowly to assume room temperature. The mixture was then made alkaline to brilliant yellow paper by addition of 30% sodium hydroxide solution and the amino azo dye was salted out with sodium chloride and filtered off.

The wet dye cake prepared above was dissolved in water and heated at 60°-70° C., for 2-3 hours with an alkaline solution of sodium hypochlorite, into which additional alkaline sodium hypochlorite solution was fed at a rate sufficient to maintain a positive test to starch-iodide paper. After clarification of the solution with charcoal, the product was recovered by salting out, filtering and drying. It was a cream-colored powder, soluble in water with bright bluish fluorescence. The absorption maximum of this compound in aqueous solution is located at 360 millimicrons.

Example 2

16.4 parts (0.1 mol) of 2-amino-6-methyl-benzothiazole were diazotized and coupled to 27 parts of the sodium salt of Broenner's acid, and the dye was isolated as in Example 1. The orthoamino azo dye thus obtained was

dissolved in 2000 parts of water at 60° C. A solution of 50 parts of $\text{CUSO}_4 \cdot 5\text{H}_2\text{O}$ in 100 parts of water and 300 parts of concentrated ammonia (28%) was added. The mixture was then heated to reflux for 16 hours and thereafter filtered. The cake was dissolved in boiling water, filtered hot; the filtrate was decolorized with aqueous sodium hypochlorite, and the product was salted out. It was a cream-colored solid, soluble in water with bright bluish fluorescence. The absorption maximum of this compound in aqueous solution is located at 350 millimicrons.

Similar compounds may also be prepared by coupling diazotized 2-amino-6-methyl-benzothiazole to naphthionic acid (1-amino-naphthalene-4-sulfonic acid) or to Laurent's acid (1-amino-naphthalene-5-sulfonic acid), and oxidizing the amino azo dyes as above.

Example 3

16.4 parts (0.1 mol) of 2-amino-6-methyl-benzothiazole were diazotized and coupled to the sodium salt of amino-R acid (2-amino-naphthalene-3,6-disulfonic acid) as in Example 1. The obtained ortho-amino azo dye was oxidized with cupric sulfate and purified as in Example 2. The final product was a light tan powder very soluble in water with bluish fluorescence. The absorption maximum of this component in aqueous solution is located at 365 millimicrons. The compound is believed to have the formula

Similar compounds may be also prepared by coupling diazotized 2-amino-6-methyl-benzothiazole to amino-J acid (2-amino-naphthalene-5,7-disulfonic acid) or to amino-G acid (2-amino-naphthalene-6,8-disulfonic acid) and oxidizing the amino azo dyes as in Example 2.

Example 4

19.5 parts (0.1 mol) of 2-amino-6-ethoxy-benzothiazole were dissolved in an acid solution consisting of 160 parts of water and 80 parts of concentrated sulfuric acid, and diazotized, at 5°-10° C., with a solution of sodium nitrite (0.1 mol) in 50 parts of water. A solution of 27 parts (0.11 mol) of Broenner's acid sodium salt in 400 parts of water was added.

The acidity was reduced by the aid of sodium acetate to a weakly acid test on Congo red paper and the mixture was allowed slowly to assume room temperature. The mixture was then made alkaline to brilliant yellow paper by addition of 30% sodium hydroxide solution, and the amino azo dye was salted out and filtered off. The wet dye concentrate thus prepared was oxidized as in Example 2. The oxidation mixture was filtered, and the cake was suspended in water and heated for 15 min. at 90° C. with an excess of a solution of sodium sulfide in water. After filtration, the product was recovered from the filtrate by salting with sodium chloride. It was a tan powder, soluble in water with bright fluorescence. The absorption spectrum of this compound in aqueous solution is located at 370 millicrons.

Compounds of similar properties are obtained by following the same procedure as in this example, except for replacing the 27 parts of Broenner's acid sodium salt by an equal weight of (a) the sodium salt of naphthionic acid, or (b) the sodium salt of Laurent's acid.

Example 5

19.5 parts of (0.1 mol) of 2-amino-6-ethoxy-benzothiazole were diazotized and coupled to the sodium salt of amino-R acid as in Example 4. The obtained dye was

oxidized and purified as in Example 4. The end product was a light tan product, soluble in water with bright fluorescence.

Similar fluorescent compounds are obtained by applying the same procedure to the amino azo dyes obtained by coupling diazotized 2-amino-6-ethoxy-benzothiazole to amino-J acid or to amino-G acid.

Example 6.

19.5 parts (0.1 mol) of 2-amino-6-ethoxy-benzothiazole were diazotized and coupled to 27 parts of Broenner's amide (2-naphthylamine-6-sulfonamide), as in Example 4. The obtained dye was oxidized as in Example 2. The reaction mass was filtered and the cake was slurried in water made acid to Congo red paper with hydrochloric acid. This slurry was heated to 80°-90° C. to dissolve all copper salts and filtered hot. The cake was washed with water until acid-free and crystallized from Cellosolve (a lower monoalkyl ether of diethylene glycol). It was a yellow powder, soluble in Cellosolve with blue fluorescence. The absorption maximum of this compound in Cellosolve solution is located at 365 millimicrons. The product is believed to have the formula:

Compounds of similar properties are obtained if the 2-amino-6-ethoxy-benzothiazole named in this example is replaced by an equivalent weight of (a) 2-amino-benzothiazole, or (b) 2-amino-6-methyl-benzothiazole.

When the Broenner's amide in the above example is replaced by 14.3 parts (0.1 mol) of 2-amino-naphthalene, one obtains a blue fluorescent agent which may be applied to cotton or nylon from a dispersion thereof in aqueous organic solvent or in a hot aqueous bath containing a dispersing agent.

Compounds of similar nature may also be prepared according to the above procedure by diazotizing (c) 2-aminobenzothiazole-6-sulfonamide, (d) 2-amino-6-methyl-benzothiazole-5-sulfonamide, or (e) 2-amino-6-ethoxy-5-sulfonamide (obtained respectively from p-anilino-sulfonamide, 4-methyl-3-sulfamyl-aniline and 4-ethoxy-3-sulfamyl-aniline, according to the Kauffmann et al. procedure above mentioned), coupling to 2-amino-naphthalene or to 2-naphthylamine-6-sulfonamide, and then oxidizing as in Example 2.

Example 7

26.6 parts (0.1 mol) of 2-amino-6-methyl-benzothiazole sulfonic acid, obtained by sulfonation of 2-amino-6-methyl-benzothiazole, were diazotized, coupled to Broenner's acid and the obtained azo dye was oxidized as in Example 4. The oxidation mixture was filtered hot, treated for 15 minutes at 60°-70° C. with an excess of a solution of sodium sulfide in water and filtered hot. The product was recovered from the filtrate by salting with sodium chloride. It was a tan powder, soluble in water with bright blue fluorescence. It is believed to have the formula

If the Broenner's acid salt in the above example is replaced by 14.3 parts (0.1 mol) of 2-naphthylamine, a product of similar properties is obtained.

The compounds of the foregoing examples are suitable for incorporation into soap or synthetic detergents, and endow a fluorescent or whitening effect to cotton or nylon fabric laundered with such soap or detergent. Fabrics washed with such detergents were subjected by us to tests to determine the bleach fastness of the fluorescent effect and found to be highly satisfactory in this respect.

Tests for light-fastness, substantivity and wash-fastness were also carried out, and showed our novel compounds to compare favorably in respect to these qualities with the best fluorescents which are now on the market.

The compounds given in the above examples have been isolated as the sodium salts of the sulfonic acids. By using potassium hydroxide and potassium salts in lieu of sodium hydroxide and sodium salts, throughout, the products may be obtained as potassium sulfonates. Isolation as the free sulfonic acids can be effected by acidification of the condensation mass, and the products thus obtained may be reacted with ammonium hydroxide or any suitable organic or inorganic base, to yield the corresponding salt.

In addition to producing a whitening effect upon textile material or paper, our novel compounds may also be used for various other purposes where fluorescence or absorption of ultra-violet light is desirable, for instance to achieve fluorescent effects in costumes or stage settings, to achieve novel effects on photographic paper, as ultra-violet filters when impregnated on cellulosic films which are used for wrapping materials, etc.

We claim as our invention:

1. A compound of the general formula

wherein R is the 2-C radical of a benzothiazole selected from the group consisting of benzothiazole itself, its 6-methyl, 6-methoxy, 6-ethyl and 6-ethoxy derivatives, and the monosulfo and sulfamyl derivatives of any of these, while Q represents the 1,2-radical of a naphthalene compound of the group consisting of naphthalene, its monosulfo, disulfo, monocarboxy, dicarboxy and mono-sulfamyl derivatives.

2. An aromatic triazole compound of the formula

wherein R is the 2-C radical of 6-ethoxy-benzothiazole, while Q is the 1,2-radical of naphthalene-6-sulfonic acid.

3. An aromatic triazole compound of the formula

wherein R is the 2-C radical of 6-methyl-benzothiazole, while Q is the 1,2-radical of naphthalene-6-sulfonic acid.

4. An aromatic triazole compound of the formula

wherein R is the 2-C radical of 6-ethoxy-benzothiazole, while Q is the 1,2-radical of naphthalene-4-sulfonic acid.

5. An aromatic triazole compound of the formula

wherein R is the 2-C radical of 6-ethoxy-benzothiazole, while Q is the 1,2-radical of naphthalene-6-sulfonamide.

6. An aromatic triazole compound of the formula

70 wherein R is the 2-C radical of benzothiazole, while Q is the 1,2-radical of naphthalene-6-sulfonamide.

7. The process of producing a fluorescence agent for textile fiber, which comprises diazotizing a 2-amino-benzothiazole compound of the group consisting of 2-amino-benzothiazole itself, its 6-methyl, methoxy, ethyl and

ethoxy substitution derivatives, and the monosulfo and sulfamyl derivatives of any of these, coupling the diazo compound thus formed to an amino-naphthalene which is adapted to couple ortho to the amino group and which is a member of the group consisting of unsubstituted amino-naphthalenes and amino-naphthalenes bearing substituents of the group consisting of sulfo, carboxy and sulfamyl, and then oxidizing the coupled compound to the corresponding triazole.

8. The process of producing a fluorescence agent for textile fiber, which comprises diazotizing a 2-amino-benzothiazole compound of the group consisting of 2-amino-benzothiazole itself, its 6-methyl, methoxy, ethyl

and ethoxy substitution derivatives, and the monosulfo and sulfamyl derivatives of any of these, coupling the diazo compound thus formed to an amino-naphthalene which is adapted to couple ortho to the amino group and which is a member of the group consisting of unsubstituted amino-naphthalenes and amino-naphthalenes bearing substituents of the group consisting of sulfo, carboxy and sulfamyl, and then oxidizing the coupled compound to the corresponding triazole, the oxidation being effected by heating the compound in an aqueous solution of ammoniacal cupric sulfate.
